SUPPLY REPLENISHING MEANS FOR
ROVING FRAMES AND THE LIKEAndrew L. Taylor, Goldville, S. C., assignor of
one-half to P. B. Mitchell, Goldville, S. C.

Application January 26, 1935, Serial No. 3,582

3 Claims. (Cl. 19—130)

This invention relates to automatic means for replenishing the supply of roving in roving frames, spinning frames and the like comprising means for supporting a plurality of packages of rovings and feeding some of the rovings to the drawing rolls and having means automatically operable upon the exhaustion of the roving on one package for placing the roving from another package in feeding position and entering its end into the drafting rolls.

It is an object of this invention to provide means for holding packages of rovings in horizontal position and feeding the roving into the drafting rolls of roving frames, spinning frames and the like, together with means for automatically entering the end of another package of rovings into the draft rolls upon exhaustion of the roving on the previous roll.

It is a further object of this invention to provide means for automatically replenishing the supply of rovings being fed to the draft rolls of roving frames, spinning frames and the like, upon the exhaustion of the supply from some of the packages, thus drawing the rovings from other packages.

Some of the objects of the invention having been stated, other objects will appear as the description proceeds, when taken in connection with the accompanying drawings, in which:

30 Figure 1 is a vertical sectional view through the upper portion of a spinning frame showing my invention applied thereto;

Figure 2 is a plan view taken along the line 2—2 in Figure 1;

35 Figure 3 is a vertical sectional view taken through the upper portion of a spinning frame and looking at the opposite side of the parts as shown in Figure 1;

Figure 4 is an enlarged detailed view showing 40 the yarn clamping means which is operated by the upper unit of the yarn carrier.

Referring more specifically to the drawings, the numeral 10 indicates a portion of a roving frame, spinning frame, and the like upon which is mounted a board 11 and filler strip 12. Resting on top of filler strip 12 is a conventional lower creel board 13 which is adapted to support the lower unit of my invention and also mounted 45 on said board 13 is a supporting member 14 which projects upwardly and supports creel boards 15 and 16. The spinning frame 10 supports a longitudinal angular member 17 upon which are mounted a plurality of roll stands 18 having conventional lower draft rolls 19, 20 and

21 and upper draft rolls 22, 23 and 24 rotatably mounted therein.

A thread board 25 is secured to angular member 17 and this board has eyelets 26 therein through which the roving is adapted to pass to the ring rail 27 and onto the yarn holder 28.

The parts thus far described are conventional, and are recited in order to disclose my invention more clearly. Heretofore, it has been the practice to mount the packages of roving for rotation in a vertical position between the creel boards 13, 15 and 16 and draw the roving from these packages through the draft rolls which are mounted in the roll stands to wind the yarn onto the quill or bobbin 28. I have devised a 10 method and means whereby the packages of rovings may be laid in a horizontal position and the roving fed therefrom in timed relation to the draft rolls, and also means are provided whereby the 15 rovings may be replenished upon exhaustion of the roving on a package. This replenishment is 20 done automatically and is effected by the empty roving holder which falls down and trips a mechanism to be later described, which will cause a new package of roving to fall into position and be 25 fed to the draft roll.

In my disclosure, I have shown two units 30 and 31 which are mounted on creel boards 13 and 15 respectively. The parts in both of these units are very similar, therefore, unit 30 will 30 be described, and like reference characters will be given to similar parts in unit 31 with prime notations added.

By referring to Figure 1 it is seen that the draft roll 19 has a sprocket 35 fixedly mounted thereon upon which is mounted a sprocket chain 36, said chain 36 being adapted to rotate on a second sprocket 37 which is of the same size as sprocket 35. This sprocket 37 is fixedly mounted on a restricted end 38a of roll 38 which roll is 40 mounted for rotation in sidewalls 39 and 40. Roll 38 has a companion roll 41 which also has its ends rotatably mounted in frames 39 and 40 and is disposed in spaced relation to roll 38 so that a roving holder 42 with no roving thereon 45 will pass between these rolls but when there is any roving on the holder 42 the rolls 38 and 41 will support the packages of roving in an elevated position. It should be noted that the rolls 38 and 41 have restricted portions 38a and 41a 50 respectively, which allows the butt end of holder 42 to pass between these rolls when the roving has been exhausted. This feature also allows the roving holder such as a quill 42 to be supported 55 in a horizontal position at all times by the rolls 55

38 and 41 when the roving on the quill has become almost exhausted.

When the quill 42 is filled with roving 43, as shown in Figure 3, the roving is fed from this 5 quill 42 since the sprocket chain 36 is driven by the rear draft roll 19 and this sprocket chain also turns the roll 38 to cause the packages to 10 rotate in a like manner. The roving 43 passes from the quill 42 over the longitudinal shaft 44 which is also mounted on the roll stand 18 and then through a suitable hole in oscillating bar 45. The roving 43 is then passed between the draft rolls 19 and 24 inclusive, and onto quill 28.

A longitudinal shaft 46 is fixedly mounted in 15 supports 39 and 40 and is adapted to cooperate with a leaf 48 rotatably mounted on shaft 47, which shaft is fixedly mounted in members 39 and 40.

It will be noted in Figure 3 that the left-hand 20 end of leaf 48 is heavier than the right-hand end and when there is no weight resting on the right-hand end thereof the leaf 48 will assume a horizontal position and rest against the pin 50 in sidewall 39. When a package 49 of roving is 25 placed between the leaf 48 and the shaft 46, a suitable lever 51 is adapted to have its upper hooked portion engage the left-hand portion of the leaf 48 and to hold it in a horizontal position. The lever 51 is mounted for oscillation on a shaft 30 52, said shaft 52 being fixedly mounted in sidewalls 39 and 40.

The lower end of lever 51 has a link 53 pivotally connected thereto which link projects to the left in Figure 3 and is pivotally connected to the upper 35 end of a lever 54 secured to leaf 55. A spring 56 has one end thereof secured to leaf 55 and the other end secured to the sidewall 39 to normally hold the leaf 55 in the position shown in Figure 3. Leaf 55 is mounted for oscillation on longitudinal 40 shaft 58 which in turn is fixedly secured in members 39 and 40.

The leaf 55 also has an upwardly projecting lever 59 which has pivotally secured to the upper 45 end thereof a horizontally disposed link 60, said link 60 projecting to the left and being pivotally mounted on the lower end of a lever 61. Lever 61 is pivotally mounted on shaft 62, said shaft 62 being fixedly mounted between sidewalls 39 and 40 and the upper end of lever 61 is adapted to 50 slidably contact a pin 63 fixedly secured in stationary jaw 64 of roving clamp 65. This clamp 65 has a movable lower jaw 66 pivoted thereto by pin 67 and a suitable torsion spring 68 is adapted to be confined around the pin 67 and engage the movable jaw 66 to normally force it at all times 55 against the lower end of stationary jaw 64 to clamp roving 49a.

The clamp 65 is secured to a block 70 which in 60 turn is slidably mounted on a pin 71 having an enlarged head portion 78 and being secured in traverse bar 45. A spring 79 has one end thereof secured to the block 70 and its other end secured to the enlarged portion 78 of pin 71 and it is seen 65 that this spring will normally pull clamp 65 to the right in Figure 3. When the roving 43 has all been removed from the spool or quill 42, the quill will pass between the rolls 38 and 41 and fall upon the leaf 55 (see Fig. 3). When this is done 70 the leaf 55 will assume the dotted line position and cause the members 54, 53, 51, and 48 to likewise assume the dotted line position, thereby allowing the package of roving 49 to fall downwardly and be guided to a position which the roving 43 and spool 42 now occupy in Figure 3

by means of suitable guides 80 secured to the sidewall members.

The members 80 are adapted to support the ends of the spool and prevent it from falling out of its proper path. It will be noted that the 5 package of yarn or roving 49 has the end of its strand 49a engaged by the clamp 65. At the same time that the package of yarn or roving 49 is allowed to move downwardly onto the rollers 38 and 41 the link 60 will be moved to the right in 10 Figure 3, thereby causing the upper end of lever 61 to force the pin 63 and the clamp 65 to the left.

When the end of the roving 49a has been presented to the draft rolls 19 and 22, the beveled 15 prong 82 on the bottom of movable jaw 66, will engage shaft 44 and cause the clamp 65 to release the end of the strand 49a. It is therefore seen that the strands on the package 49 will then be fed to the rolls in the same manner that the 20 strand 43, which is on spool 42 was fed previously. It should be noted that clamp 65 is secured to oscillating bar 45 and is adapted to oscillate with the bar.

Lever 61 is stationary but the upper end thereof has a sliding contact on the pin 63 which will allow this oscillation to take place without interfering with the stationary parts. The upper unit 31 is similar in most respects to unit 30, just described, and a description of these parts is not 30 deemed necessary, but it might be stated that similar parts will bear like reference characters with the prime notation added. However, it should be noted that a slightly different arrangement must be made for the operation of this 35 unit with its clamp 85 which is shown in Figure 4 and which is similar in all respects to the clamp 65 just described and has identical reference characters.

The lower end of leaf 55' has integral there- 40 with an arm 86 having a slot 86a in the lower end thereof. The upper end of a lever 87 has a bolt therein which penetrates this slot. Lever 87 is pivotally mounted on a longitudinal, horizontally disposed shaft 88. This shaft 88 is like- 45 wise mounted in end walls 39 and 40 and the lower end of lever 87 is pivotally secured to horizontally disposed link 60, (see Fig. 4).

When the quill 42' has its roving exhausted therefrom, it will pass between the rollers 38' 50 and 41' and fall upon the leaf 55' to cause this leaf to assume the dotted line position. This, in turn, will cause arm 86 and the lever 87 to assume their dotted line position and thereby causing the lever 87 to rotate a slight amount in 55 a counter-clockwise manner. This rotation will move the link 60 in Figure 4, to the right which will cause counter-clockwise motion of lever 61 thereby pushing the clamp 85 to the left of pin 71 and introducing the strand 49a to the draft 60 rolls 19 and 22. It is evident that when the quill falls off of the leaf 55 that the spring 56' will cause the leaf 55' to assume the horizontal position and thereby cause the lever 51' to latch the leaf 48' in its original position, since the left-hand end of leaf 48' is heavier than the right-hand end (see Fig. 3).

In a like manner the springs 79 will move the clamps 65 or 85 to their original positions after the quill has fallen off of the leaf 55 or 55'. 70 When this is done the parts 46 and 48 are in position for placing a new package of roving thereon and threaded into the clamping means 65 or 85.

The upper unit 31 is driven simultaneously 75

with the lower unit 30 and at the same rate of speed by means of sprocket 90 which is mounted on restricted portion 38a. A suitable chain 91 is mounted on sprocket 90 and also on another 5 sprocket 92 which is identical to sprocket 90, said sprocket 92 being fixedly mounted on the end of restricted portion 38a'.

The upper units 31 feed their rovings to alternate sets of bosses on the drawing rolls while 10 the lower units 30 deliver their rovings to the other bosses on the drawing rolls. There is one roving fed from a unit at a time while a second roving has its end held by the clamp for feeding it to the bosses upon exhaustion of the roving 15 being fed through the set of bosses.

In the drawings and specification there has been set forth a preferred embodiment of the invention, and although specific terms are employed, they are used in a generic and descriptive 20 sense only, and not for purposes of limitation, the scope of the invention being set forth in the appended claims.

I claim:

1. In a roving frame, spinning frame and the 25 like having drafting rolls, a pair of spaced rollers driven by the drafting rolls for supporting packages of rovings, other means for supporting a package of rovings, means for engaging the end of the rovings on said other package and feeding 30 same to the drafting rolls, means operable upon exhaustion of the rovings on the first package for releasing the second package, means for guiding the second package onto said spaced rollers, and

means for moving the means engaging the end of the roving on said second package to feed its roving into the drafting rolls.

2. In fiber preparation machinery having drafting rolls, means for holding a package of 5 fibers in strand form, means for turning the package to feed the strand thereon into the drafting rolls, other means for holding a second package in reserve, feeding means for engaging the end of a strand on said other package, and 10 means operable upon exhaustion of the strand on the first package for moving the second package into the position occupied by the first package and also moving the feeding means to cause its strand to be fed to the drafting rolls. 15

3. In fiber preparation machinery having drafting rolls, a pair of spaced rollers driven in timed relation to the drafting rolls and being adapted to support a holder filled with rovings thereon, a trap door mechanism for holding a 20 second holder filled with rovings, a chute for guiding said second holder onto said rollers, clamp means for holding the end of the roving on said second holder, means operable by the 25 holder of the first package when it falls between the spaced rollers upon exhaustion of the rovings thereon for tripping said trap door mechanism to cause the second holder to move onto said spaced rollers and to move the clamp means towards the drafting rolls to feed the end of the roving from 30 the second holder to the drafting rolls.

ANDREW L. TAYLOR.
